UNITED STATES PATENT OFFICE

168,698

CHILD'S PAJAMAS

Seymour A. Marrow, Scarsdale, N. Y., assignor to Harwood Manufacturing Corp., New York,
N. Y., a corporation

Application July 31, 1952, Serial No. 20,863

Term of patent 7 years

(Cl. D3—17)

To all whom it may concern:

Be it known that, I, Seymour A. Marrow, a citizen of the United States of America, residing at Scarsdale, county of Westchester, and State of New York, have invented a new, original, and ornamental Design for a Child's Pajamas, of which the following is a specification, reference being had to the accompanying drawing, forming part thereof.

Fig. 1 is a front view of a child's pajamas showing my new design, and

Fig. 2 is a rear view thereof.

I claim:

The ornamental design for a child's pajamas, substantially as shown.

SEYMOUR A. MARROW.
